A. J. BROOKS

AIR HOSE PROTECTOR

Filed March 30, 1921

UNITED STATES PATENT OFFICE.

ANDREW J. BROOKS, OF ST. JOSEPH, MISSOURI, ASSIGNOR, BY MESNE ASSIGNMENTS,
TO STANDARD OIL COMPANY, INDIANA, OF CHICAGO, ILLINOIS, A CORPORATION
OF INDIANA.

AIR-HOSE PROTECTOR.

Application filed March 30, 1921. Serial No. 456,919.

To all whom it may concern:

Be it known that I, ANDREW J. BROOKS, a citizen of the United States, residing at St. Joseph, in the county of Buchanan and 5 State of Missouri, have invented certain new and useful Improvements in Air-Hose Protectors; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to fluid dispensing apparatus and more particularly to air hose protectors, the principal object of the invention being the protection of air hose commonly employed for inflating automobile tires, the present application being a continuation, in part, of a joint application filed by Oliver M. King and myself March 10, 1919, Serial No. 281,893.

In the accompanying drawings, wherein 25 embodiments of the invention are illustrated:—

Fig. 1 is a perspective view of an apparatus embodying the invention, the housing being broken away to show the contained parts.

Figs. 2 and 3 are enlarged detail perspectives of the upper and lower brackets and parts associated therewith.

Fig. 4 is a vertical section of the apparatus.

Referring more in detail to the drawings:

1 designates a housing, preferably supported on a concrete base 2 and provided with a bottom opening 3, and side openings 40 4 and 5 through which access may be had to the working parts for installation, inspection and repair. The respective openings are provided with a cover plate 6 and doors 7, 7'.

45 Located within the housing are upper and lower brackets 8, 9, preferably comprising end flanges 8', 9', that lie vertically against opposite walls of the housing and are attached thereto by bolts 10. Mounted on 50 the upper bracket 8 is a pulley block 11, carrying a wheel 12, and formed integrally with the lower bracket 9 is a pulley block 13, carrying a wheel 14.

A cable 15 passes over the pulley wheel 55 12 and runs through openings 16, 17 in the

bracket 8. Secured to one end of the cable is a hose guide 18, preferably consisting of a pulley block 19 and its wheel 20, and secured to the other end of the cable is a weight 21 that counterbalances the guide 60 and the hose carried thereby, as presently described.

Run over the wheel 20 in the hose guide and over the wheel 14 on the stationary pulley block 13 is a hose 22, one end of which 65 is connected with an air supply pipe 23. The other end of the hose is run through an opening 24 in the housing so that it may be accessible from the exterior, the free end of the hose being provided with a nozzle 40. 70

To facilitate use of the hose and protect it from wear, I line the opening 24 with anti-friction rollers 25, having axles 26 carried by flanges 27 on a plate 29 attached to the housing. 75

The hose guide is guided in its vertical travel by a rod 30, suspended from the upper bracket 8 and connected with the lower fixed pulley block 13 and the weight is guided by a hollow standard 31, carried 80 by an upper bracket 32 that is attached to the housing and by a clamp 33 that is attached to the lower bracket 9.

It will be understood from the foregoing that the weight 21 will normally hold 85 the guide 18, together with the hose 22, in the position shown, and that when the free end of the hose is drawn to one side, as is done in inflating a tire, the upper part of the loop of the hose is drawn down, thereby pulling the cable 15 around the pulley 12 and raising the weight 21. When the free end of the cable is released the weight draws the parts back to the position shown in the drawings. 90

Having thus described my invention, what I claim as new therein and desire to secure by Letters-Patent is:

1. A device of the character described, comprising a housing having an opening 100 therein, a tubular standard within the housing, a weight slidable within the standard, a cable connected at one end to the weight, a pulley block connected to the other end of the cable, a pulley in said block, a pulley block fixedly mounted adjacent the top of the standard, a pulley in said block secured to the standard, over which the cable passes, a pulley block fixed to the standard near the bottom thereof, a pulley in said last 105 block, a pulley block fixed to the standard near the bottom thereof, a pulley in said last 110 block.

named block, and an air hose passing over the cable-connected pulley and over the fixed pulley, one end of the hose projecting through the opening in the housing.

5. 2. Air supply apparatus for vehicle service stations, comprising an upright hollow standard, an air supply duct and a guide pulley located near the base thereof, a traveling pulley adapted to travel vertically adjacent to the standard; a housing for said traveling pulley, a fixed pulley mounted adjacent the top of said standard, a cable secured to said pulley housing and passing over the fixed pulley at the top of the standard, a counter-weight fastened to the cable and located within and guided by said hollow standard for constantly urging the traveling pulley to rise, and an air hose coupled at one end to said supply duct and passing thence over the traveling pulley and thence under the guide pulley.

- 10 3. In a fluid dispensing apparatus, the combination of a hollow standard or col-

umn, a pulley supported adjacent the upper end of the column, a cable extending over said pulley and into the column, a hose guide attached to the end of the cable outside the column, a weight attached to the end of the cable within the column, and a flexible hose supported by said hose guide and provided at one end with means for attachment to a supply pipe, substantially as and for the purpose described.

15 4. A device of the character described, comprising a casing, a hollow standard within the casing, a hose supporting pulley in guided relation with respect to the standard, a weight connected thereto and movable within the hollow standard, and a complementary pulley below the first named pulley and supported by the standard, the two pulleys being adapted to receive a hose 20 passing around them so as to normally maintain the hose taut.

25 In testimony whereof I affix my signature.
30 ANDREW J. BROOKS.
